UNITED STATES PATENT OFFICE.

DAVID H. WHITTEMORE, OF LYNCHBURG, VIRGINIA.

HAY AND STRAW CUTTER.

Specification of Letters Patent No. 29,930, dated September 4, 1860.

To all whom it may concern:

Be it known that I, DAVID H. WHITTEMORE, of Lynchburg, in the county of Campbell and State of Virginia, have invented a 5 new and useful Machine for Cutting Hay, Straw, Cornstalks, &c.; and I do hereby declare that the following is a full, clear, and exact description of the construction and operation of the same, reference being had 10 to the annexed drawing, making a part of this specification, in which—

Figure 1 is a perspective view showing one side, the front, and top of the machine, Fig. 2 a plan front view, Fig. 3 a top view, 15 and Fig. 4 a sectional side view.

The same letters in different figures refer to the same parts of the machine, but represented by different views.

In Fig. 1, A, A, A, is the wood frame. 20 B and C, C, C is the metallic frame, which is intended to be made of cast iron, and is held together, and to the wood frame by two screws (seen) on each side, which frame (B and C, C, C,) serves, as journal boxes to hold 25 the arbor i, to which is attached, or cast, three flanges of spiral form, one of which is represented in Fig. 1 by D, E and F, D being the side, E the edge and F a projection upon one side of the flange, which serves to ease 30 the spring G down to its proper place after having been raised to a point above by the revolving flange, thereby preventing noise, &c.

The top or circular part of the frame B is 35 mainly to cover up and give a neat appearance to the machine at that point, but prevents any straw, &c., from working or coming through at any other place than the place intended, it also serves to strengthen

40 or hold more firm that part of the frame C, below, to which the knife is attached, said knife not being seen in Fig. 1, but which runs the length of the frame C, and is attached to the other or lower side of said 45 frame with the bevel side down, by which bevel and edge of said knife said flanges revolve, pressing the feed against the edge of the knife, causing it to be cut off.

The two screws in front and center of 50 the frame C, serve to adjust said knife to the revolving flanges.

The machine is put in motion by the crank i, and handle R, the balance wheel k, upon 55 the opposite end of the arbor i, serving to give a uniform and steady motion to the machine while in operation. The board G

hinged at T, T, is made to vibrate while the machine is in motion, by the revolving flanges (one of which is seen at D) or by the flanges and straw between pressing 60 against it, the object of this board G, being to keep the ends of the straw or article being cut below the level of the edge of the knife o, so that the revolving flange, with the help of the teeth upon the same, will 65 draw it forward and under the knife, and between the knife and flange, so that the latter may press it against the former, causing it to be cut off. A spiral spring is attached at H to this board, which runs down 70 and under the machine, (there is also one on the opposite side but not seen in Fig. 1,) which serves to accomplish the object just referred to, and which will be hereafter 75 represented by figures.

Fig. 2, is a front view of the machine, showing the crank j, in an upright position, the handle R, the wood frame A, A, A, the front part of the metallic frame C, C, C, and the back or circular part B, the two 80 screws in the center of the frame C, which serve to adjust the knife o, to the flanges, the edge of which knife is represented by the straight line just below said screw. The slotted edge of the spring board G, which 85 was referred to in Fig. 1, is also seen below said line, which represents the edge of the knife, the slots in said board being cut to allow the teeth M &c. to project through them while in motion, thereby causing 90 them to get a strong hold upon the article being cut, and which is to be drawn forward by said teeth, and also to prevent the teeth from coming in contact with said board while in operation.

The teeth M, M, M, M, are seen projecting 95 through the flanges and below the slotted edge of the spring board G, each tooth being immediately in front of, and in revolving passes through, the edge of each of said slots, 100 in said board G, the teeth being with the help of the revolving flanges and the spring board above, the means used to draw the feed forward between the revolving flanges, and the cutting knife, thereby making it a 105 perfect and regular self-feeding machine.

The flange D below is seen upon the opposite side from the one above. Therefore the teeth are not seen.

Fig. 3 is a top view of the machine, in 110 which the top or circular part of the metallic frame B is removed, (the points B, B,

representing where it was cut off), which allows the whole of the spring board G, to be seen, and the ends of the two springs, H, H, are seen attached to the board, the other ends being attached to the wood posts of the frame below. The edge of the knife o, is also seen between the slotted edge of the board G, and the metallic frame C, the knife being held under the frame C, by screws the points of which are seen projecting through at P, P. The two screws Q, Q, in front of the frame C, are for the purpose of adjusting said knife to the flanges, the points of the screws coming against the back of it.

15 The dotted line V, V, shows where the machine is cut to give the sectional view as represented in Fig. 4.

Fig. 4 being a side sectional view, the position of the spiral spring H, H, H, is seen (the other spring upon the opposite side being removed). One end of this spring is attached to a pin in the wood post below, the other end runs through the side board of the hopper, and fastened to the spring board G, before described, a section edge view of which is seen by G, T. It is hinged at T, the end G, being allowed to vibrate, as the flanges, or flanges and feed may operate upon it, the flanges raising it, while the springs draw it back to the position as seen. In this figure, an edge view of the metallic frame C, C, is seen, into which the screw P, is inserted to hold the knife to the frame, the points of which at P, P, in Fig. 3 are seen. They pass through the knife o, and screw in to the frame C. Also one of the adjusting screws, Q, is seen passing through the frame C, the point coming against the back of the knife o, o. Also is seen in Fig. 4, arbor i, and the three flanges with the teeth M, M, M, inserted, and their relative position with the spring board G, the knife o, o, the metallic frame B and C, C.

40 In operating my machine the feed passes through at, and in the direction of, the arrow U, the ends of the feed reaching above the flanges, and teeth, M &c., and between the flanges and the spring board G. The teeth M, revolving in the direction of the arrow S, are forced into the hay, or feed, and by their motion forward, the feed with them is drawn under the knife o, until the edge of the flanges passes by the edge of the knife o, o, (the feed being between them) it is cut off. When the teeth are in the act of raising and drawing the feed forward, the feed is pressed against the spring board G, and causes it to be raised to the position rep-

resented by the dotted line above, and as the feed is cut the ends of that lying in the hopper, is raised above the edge of the knife o, o, and in a position to prevent its being acted upon by the next revolving flange, and teeth, to draw it forward, but as the flange is through cutting, or has passed from under the spring board G, and under the edge of the knife o, o, the spiral springs one of which is seen by H, H, H, operate upon the board G, and force it down from the position of the dotted lines above, to the position as now seen below in Fig. 4, and with it forcing down the hay (lying in the hopper) or the ends of it, below the edge of the knife, that it may be drawn under, and that the next revolving flange with its teeth, may take hold of it, to draw it forward, and press it against the knife to cut it as before, and thus the operation is continued, getting as many cuts with one revolution, as I have flanges upon the arbor. These flanges I propose to make of cast iron or cast iron with steel or wrought iron fastened to them.

20 By this simple arrangement, I am enabled to get from one to four cuts at a revolution, according to the number of flanges, with only one straight knife, and no gearing, no feed rolls, or other complicated machinery, and the power is applied direct, causing it to work very easily. These teeth can also be arranged upon a cylinder of cutting knives, 30 in such a manner as described, and by having a stationary bed knife, against which the cutting knives press, to cut the feed, the same result is obtained, viz., dispensing with feed rolls, or other gearing to draw in the feed.

35 Having thus described my machine, what I claim as my invention, and desire to secure by Letters Patent, is—

1. So arranging the feed teeth M, M &c., upon a revolving cylinder or flanges, that said cylinder or flanges, will, while revolving, with the help of said teeth, both draw the feed forward, and in passing by a stationary knife, cause it to be cut off, substantially as described.

2. Combining with said cylinder, the spring board G, in the manner, and for the purpose, substantially as set forth.

3. Combining with said cylinder, and spring board, the stationary knife o, substantially as described.
